UNITED STATES PATENT OFFICE.

JOHN FRICK, OF PHILADELPHIA, PENNSYLVANIA.

PETROLEUM-BURNER.

SPECIFICATION forming part of Letters Patent No. 731,170, dated June 16, 1903.

Application filed November 14, 1902. Serial No. 131,298. (No model.)

To all whom it may concern:

Be it known that I, JOHN FRICK, a citizen of the United States, residing at Philadelphia, in the county of Philadelphia and State of Pennsylvania, have invented certain new and useful Improvements in Petroleum-Burners, of which the following is a specification.

My invention relates to improvements in petroleum-burners, and to that class in which the petroleum-oil is fed from a reservoir by gravity or by pressure to a vaporizing-tube in which the oil is converted into vapor and from which it is discharged through a nozzle into a mixing-tube and caused to commingle with air before reaching the burner-head.

My invention consists in the novel construction and arrangement of the burner-head and mixing-tube, in the vaporizer, and in a mechanism for regulating the flow of vapor from the discharge end of the vaporizing-tube, all of which will be hereinafter fully illustrated and described.

Referring to the accompanying drawings, Figure 1 represents a side elevation of my improved burner, which for convenience of illustration has been shown mounted upon an air-reservoir, with the connection between the vaporizer and reservoir in position and an air-pump and connection shown to force the oil from the reservoir to the vaporizer. It will be understood, however, that this close relationship between the burner and the reservoir is not necessary, as the latter may be located some distance away from the burner or at a considerable height above the same to furnish the required pressure. Fig. 2 illustrates an enlarged plan view of the burner removed from the reservoir. Fig. 3 shows a longitudinal section of the burner, taken on the line 3 3 of Fig. 2. Fig. 4 illustrates a transverse section on the line 4 4 of Fig. 1; and Fig. 5 shows a detached section of the discharge-nozzle, taken on line 5 5 of Fig. 3.

Referring to the reference-letters of the drawings, A represents the vaporizing-tube; B, the burner-head; C, the mixing-tube, in which the vaporized oil and air are caused to commingle, and D represents the discharge-nozzle arranged to regulate the flow of vapor from the mixing-tube.

The vaporizer A comprises a tube extending horizontally across the burner-head and

supported in lugs *b b*, provided with set-screws *b' b'*, by which the tube is detachably secured. The vaporizer A is provided at one 55 end with an oil-supply pipe A', which, as shown in Fig. 1, is connected to an oil-reservoir E and provided with an oil-regulating valve A². The opposite end of the vaporizer is provided with a discharge-nozzle D, which 60 is formed of two parts *d* and D'. The part *d*, which may be termed the "nozzle" proper, is of some length and has in the end a small discharge-orifice *d'*.

The burner-head B is made in the form of 65 a ring, the base portion B' being hollowed out and provided with a cap-plate B², and at the point of junction are a series of holes *b²*, which are formed by slotting the upper edges of the portion B'. Extending across the ring 70 and communicating with it at both ends is a conduit B³, which is provided with slots *b³*, similar to those above mentioned, and with a cover-plate B⁴, secured in place by a screw *b⁴*. At one side of the burner-head is a curved 75 depending portion B⁵, which has an opening *b⁵* to receive the mixing-tube C.

The mixing-tube C consists of a straight tube extending horizontally across the bottom of the burner-head below the conduit B³, 80 one end having a flared opening in line with the nozzle D and the other slightly reduced and driven into the opening *b⁵*, which, together with a screw *b⁶*, holds the mixing-tube firmly to the burner-body. The slidable portion D' of the nozzle is guided in a lug F, projecting out from the burner, and has on one side a rack *f*, which is operated by a pinion F' on a stem f². The slidable portion of the nozzle is also provided within a needle D², 90 which is adapted to enter the orifice *d'*, so that by operating the rack and pinion the orifice may be opened and closed to any degree to regulate the flow of vapor. The lower curved portion of the slidable tube D' or its discharge end, as will be noticed, is of much greater diameter than the orifice *d'*, so that little or no back pressure in the tube will occur to cause leakage at the point where one section of the nozzle telescopes the other. 95 The movement of the tube D' in regulating the discharge of vapor is only slight, the movement being more particularly for the purpose of cleaning the small orifice and keeping it

it free from carbon deposits, so that at the two extreme positions—open and closed—the distance traversed would not change the relative position of the end of the nozzle D' and the mouth of the mixing-tube C to render the device inoperative.

Having described my invention, what I claim, and desire to secure by Letters Patent, is—

- 10 A petroleum-burner, comprising, in combination with the burner - head, vaporizer, and mixing-tube thereof, a discharge-nozzle

formed of two telescopic tubular parts, one of which is secured to the vaporizer and provided with a valve opening and seat, and the other being slideable over the first-mentioned part and provided with a valve-needle, substantially as specified.

In testimony whereof I affix my signature in presence of two witnesses.

JOHN FRICK.
